CLAIM

The ornamental design for a massage spike appliance, as shown and described.

DESCRIPTION

FIG. 1 is a perspective view of a massage spike appliance, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a view showing a state of use of the massage spike appliance with other massage spike appliances.

The broken lines shown in the figures depict environmental structure and boundaries that form no part of the claimed design.

1 Claim, 8 Drawing Sheets
